TOY FISHING DEVICE

Joe D. Waddell, Charlotte, N.C.

Application January 29, 1958, Serial No. 49,439

Term of patent 14 years

(Cl. D34—15)

Figure 1 is a top perspective view of a toy fishing device embodying my new design with the fishing pole in lowered position;

Figure 2 is a reduced elevation looking at the opposite side of Figure 1 with the fishing pole in raised position.

The characteristic features of the invention reside in the portion shown in full lines.

I claim:

The ornamental design for a toy fishing device, substantially as shown, and described.
